CLAIM

The ornamental design for a fluid dispensing container, as shown and described.

DESCRIPTION

FIG. 1 is a perspective view of a fluid dispensing container, showing my new design;

FIG. 2 is a perspective view of my new fluid dispensing container stacked five high on a lawnmower deck, the items in dotted lines forming no part of the invented design;

FIG. 3 is a top view of the fluid dispensing container of FIG. 1;

FIG. 4 is a rear elevational view thereof;

FIG. 5 is a side elevational view thereof, the opposite side being a mirror image;

FIG. 6 is a front elevational view thereof; and,

FIG. 7 is a bottom view thereof.
